FORM FOR WINDINGS AND THE LIKE

William F. Stahl, Evanston, Ill.

Application October 15, 1942, Serial No. 462,075

7 Claims. (Cl. 242—119)

This invention relates to a form for windings and the like, and more particularly to a bobbin or spool construction which is particularly adapted to be used as a form to receive electrical windings, such as coils.

An object of the invention is to provide a form for windings and the like wherein a plurality of flanges are disposed in spaced relation on a tubular core, with the flanges being fixed in longitudinal position by spacing members received on the core. Another object is to provide a plurality of flanges on a core and spacing members received on the core between certain flanges so that the flanges and spacing members are brought into tight engagement by the swaging of the core which fixes the flanges in position thereon.

Another object of the invention is to provide in a form for windings and the like wherein flanges are received on a tubular core, flanges equipped with slots for receiving electrical connections and the like. Yet another object is to provide in a form for windings and the like adapted to receive a plurality of coils, means for separating all of the coils by insulating material while at the same time providing slots or grooves for receiving electrical connections and the like. A further object is to provide in a form for windings and the like, spacing members and flanges received on a tubular core, with the spacing members and flanges being equipped with interlocking means for preventing rotation of the flanges with respect to the spacing members.

Other features and advantages will appear from the following specification and drawing, in which—

Fig. 1 is a perspective view of an embodiment of the invention; Fig. 2 is a perspective view of a spacing member used in the invention; Fig. 3 is a front elevational view of one of the flanges; Fig. 4 is a collective view in section of the various parts used in assembling the device; Fig. 5 is a longitudinal sectional view of the device; Fig. 6 is a perspective view of a modified form of spacing member; Fig. 7 is a front elevational view of a modified form of flange; and Fig. 8 is a vertical sectional view of a form of the invention embodying the flanges and spacing members of Figs. 6 and 7.

The invention contemplates a simple and inexpensive construction for bobbins or the like for receiving electrical windings wherein a plurality of coils may be received on a single form and the coils separated by insulating material. At the same time, the form provides slots or grooves for receiving the electrical connections of each of the coils.

In the embodiment of the invention shown in Figs. 1 to 5, a tubular core 10 of laminated paper or other suitable material receives a plurality of centrally apertured flanges 11. Spacing mem-

bers 12 are applied to the core between certain of the flanges 11.

The core 10 may be of any suitable construction, but is preferably formed of laminated strips 5 of paper helically wound in tubular form. The core, of course, may be circular in cross section or may be polygonal or rectangular, if desired, and the term "tubular" is intended to include polygonal cross sectional shapes.

10 The flanges 11 are centrally apertured and are provided with tongues 13 extending radially inwardly from the periphery of the central aperture of the flange. The tongues 13 are preferably equidistantly spaced about the periphery of the central aperture and provide recesses 14 therebetween. The flange 11 may be equipped with a slot 15 which extends from the central portion of the flange to the outer periphery thereof. Preferably, the slot 15 is a straight slot which 20 communicates at one end with the central aperture of the flange and at the other end extends through the outer periphery thereof. As shown, the slot may be disposed at a slight angle with respect to a radial line of the circular flange. 25 The flange may be made of any suitable material, such as paper or composition material which is electrically insulating in character.

The spacing member 12 is tubular in character and conforms in cross section construction to the 30 tubular core 10. The spacing member 12 may consist of laminated paper or other suitable material. The inside diameter of the spacing member is only slightly greater than the outside diameter of the core 10 so that the spacing member 35 may be snugly received about the core 10. At its ends, the spacing member may be equipped with longitudinally-projecting tongues 16 which may be equidistantly spaced about the periphery of the spacing member 12 providing recesses 17 40 therebetween.

Preferably, each spacing member is equipped with a pair of the longitudinally-projecting tongues which are disposed in diametrical opposition to each other at each end of the member. 45 The length of each of the tongues 16 may be approximately twice as great as the thickness of the flanges 11. By reason of this construction, each of the tongues 16 may be received within a recess 14 of a flange 11 and will extend 50 through and engage two adjacent flanges.

Additional flanges 18 of a slightly different construction may be used in the bobbin. The flanges 18 may be of the conventional construction wherein a flange of insulating material is 55 provided with a central aperture. If desired, the outwardly-extending slots may be omitted in the flanges 18. However, the flanges 18 may be provided with the same radial tongues and recesses as the flanges 11. Only two of the four recesses in the flanges 18, however, will be engaged

by the tongues 16 of the adjacent spacing member 12. Similarly, only two of the recesses 14 in the flange 11 at the end of the bobbin will be engaged by the tongues 16 at the end of the adjacent spacing member 12.

The bobbin or form for windings may be assembled by placing the flanges 18 and 11 and the spacing members 12 on the core 10 in the arrangement set forth in Fig. 4. A flange 18 may be placed at one end of the core, and a flange 11 placed immediately adjacent the flange 18 on the inner side thereof. Three spacing members 12 may be placed on the core 10, with a pair of flanges 11 being placed between each of the spacing members 12. A flange 11 and a flange 18 may be then placed at the other end of the core.

The apertures in the flanges 18 and 11 are of such size that the flanges are snugly received on the core 10. In the case of the flanges 11, the ends of the radial tongues 13 snugly engage the outer surface of the core 10. Similarly, the spacing members 12 are snugly received on the core 10.

In the assembly of the device, the tongues 16 on each of the spacing members 12 are received in interlocking relation with the recesses 14 in each adjacent pair of flanges, the tongues 16 of each spacing member extending through a pair of adjacent flanges. The spacing members may be arranged so that the adjacent tongues 16 of adjacent spacing members are disposed at angles of approximately 90° with respect to each other. In this manner, the tongues 16 of the spacing member 12 adjacent the end of the flange are received within the upper and lower recesses 14 of the flanges 11, while the tongues 16 of the spacing member 12 disposed in the center of the bobbin are received within the side recesses of the flanges 11. This construction provides for a complete interlock throughout the device so that the spacing members and flanges are fixed in position with respect to each other. The slots 15 are so arranged in the flanges 11 that in the assembly of the bobbin or form, the slots of adjacent flanges 11 are out of register with each other. In this manner, a continuous insulating surface is provided between each of the spacing members and between the coils which may be placed thereon.

The assembly is completed by outwardly swaging the ends 18 and 20 of the core 10 to bring the outwardly-swaged ends into engagement with the flanges 18 at the ends of the core. The flanges and spacing members are of such width that the outward swaging of the ends of the core causes the flanges and spacing members to be brought into tight engagement with each other.

In the embodiment of the invention shown in Figs. 6, 7 and 8, the construction and arrangement of the core 21, spacing members 22, and flanges 23 are the same as in the embodiment of Figs. 1 to 5, except that the spacing members 22 and flanges 23 are not provided with the interlocking tongues and recesses. When the assembly of this form of the invention is completed by outwardly swaging the ends 24 and 25 of the core 21, the flanges 23 and spacing members 22 are brought into tight frictional engagement, but may, under sufficient pressure, be rotated with respect to each other. The flanges 23 are identical in construction and may be used at the ends of the core as well as in the intermediate portions thereof.

Although the invention has been described in connection with specific embodiments, it will be apparent that these embodiments have been described in detail for the purpose of illustration only. Changes and modifications, therefore, may be readily made in the construction and arrangement of the device without departing from the spirit and scope of the invention.

I claim:

1. A form for windings and the like, comprising a tubular core, a plurality of centrally apertured flanges on said core with the core extending through and fitting snugly within said apertures, a pair of said flanges being disposed at one end of the core, another pair of flanges being disposed at the other end of the core, and the remaining flanges being disposed at intermediate portions of the core, the flange of each of said end pair of flanges adjacent the central longitudinal portion of the core and each of the intermediate flanges being equipped with a slot therein extending from the central portion of the flange to the periphery thereof, and tubular spacing members of internal diameter only slightly greater than the external diameter of said core received on said core, one of said spacing members being adjacent each end of the core and engaging the slotted end flange, the other end of each of said spacing members engaging an intermediate flange, said core having outwardly swaged ends which engage the adjacent flanges and lock the flanges and spacing members in engagement with each other.

2. A form for windings and the like, comprising a laminated paper tubular core, at least three centrally apertured flanges received on said core with the core extending through and fitting snugly within said apertures, one of said flanges being disposed at each end of said core and the other flange being disposed at an intermediate portion of the core, a pair of tubular spacing members of internal diameter only slightly greater than the external diameter of the core received on said core, each of said spacing members being disposed between a pair of flanges, and means carried by said spacing members and flanges for securing the same in interlocking relation to prevent relative rotation thereof with respect to the axis of the core, said core having outwardly swaged ends which engage the flanges adjacent the ends of the core and lock the flanges and spacing members in engagement with each other.

3. A form for windings and the like, comprising a laminated paper tubular core, a plurality of pairs of centrally apertured flanges received on said core with the core extending through and fitting snugly within said apertures, one of said pair of flanges being disposed at each end of the core and the other pairs of flanges being disposed at an intermediate portion thereof, the inner flange of each pair of end flanges disposed adjacent the central longitudinal portion of the core and each of the intermediate flanges being provided with a slot extending from the central portion of the flange to the periphery thereof, the slots in each pair of slotted flanges being out of register with each other, tubular spacing members of internal diameter only slightly greater than the external diameter of said core received on the core, each of said spacing members being disposed between a pair of flanges, and means for securing said spacing members in interlocking relation with the adjacent flanges to prevent relative rotation thereof with respect to the axis of the core, the ends of said core being outwardly

swaged and engaging the end flanges to lock the same on the core and to maintain the flanges and spacing members in engagement with each other.

4. A form for windings and the like, comprising a tubular core, an apertured flange on each end of said core with the core extending through the apertures in each of the flanges, a pair of apertured flanges received on said core with the core extending through the apertures in the flanges and the flanges being disposed together and in engagement with each other at an intermediate portion of the core, at least one of said pair of flanges being equipped with a slot extending from the central portion to the periphery thereof, said slot being disposed opposite a solid portion of the adjacent flange of said pair, and a pair of tubular spacing members of internal diameter only slightly greater than the external diameter of said core received on the core, each of said spacing members being disposed between an end flange and the pair of intermediate flanges, said core having swaged ends which engage the adjacent flanges and hold the flanges and spacing members in engagement with each other.

5. A form for windings and the like, comprising a tubular core, an apertured flange on each end of said core with the core extending through the apertures in the flanges, a pair of apertured flanges on said core with the core extending through the aperture in each of the flanges and the flanges being disposed at an intermediate portion of the core in engagement with each other, at least one of said flanges being equipped with a slot extending from the central portion to the periphery thereof, said slot being disposed opposite a solid portion of the adjacent flange of said pair, a pair of tubular spacing members of internal diameter only slightly greater than the external diameter of said core received on the core, each of said spacing members being disposed between an end flange and said pair of intermediate flanges, said core having outwardly-swaged ends each of which engages the adjacent flange and locks said flanges and spacing members in engagement with each other, and means carried by the spacing members and flanges for securing the same in interlocking relation to pre-

vent relative rotation thereof with respect to the axis of the core.

6. A form for windings and the like, comprising a tubular core, a centrally-apertured flange on each end of said core with the core extending through the apertures in each of the flanges, a pair of centrally-apertured flanges received on said core with the core extending through and being snugly received in frictional engagement with the apertures in the flanges, said flanges being disposed together in engagement with each other at an intermediate portion of the core, each of said pair of flanges being equipped with a slot extending from the central portion to the periphery thereof, and a pair of tubular spacing members of internal diameter only slightly greater than the external diameter of said core received on the core, each of the spacing members being disposed between an end flange and the pair of intermediate flanges, said core having swaged ends which engage the adjacent flanges and hold the flanges and spacing members in engagement with each other, the intermediate flanges being rotatable with respect to each other about the core against the frictional engagement of said intermediate flanges with the core and with the spacing members to bring said slots into and out of registry.

7. In a form for windings and the like, a tubular core, a centrally apertured flange received on said core with the core extending through and fitting snugly within said aperture, a pair of tubular spacing members of internal diameter only slightly greater than said core, one of said members being disposed on one side of said flange and the other of said members being disposed on the other side of said flange, said flange containing at least two tongue-receiving recesses, said one member having a tongue extending into one of said recesses and the other of said members having a tongue extending into the other of said recesses, and means for holding said members against longitudinal displacement whereby said flange is locked against rotation about said core with respect to said members.

WILLIAM F. STAHL.
